VACUUM PICK-UP FOR WAFERS

T. John Trayes, Phoenix, Ariz., assignor to
Motorola, Inc., Chicago, Ill.

Filed Mar. 28, 1974, Ser. No. 455,683

Term of patent 14 years

Int. Cl. D8—05

U.S. Cl. D8—71

FIG. 1 is a perspective view of a vacuum pick-up for wafers showing my new design.

FIG. 2 is a top view thereof.

FIG. 3 is a front view thereof.

The side opposite that shown in FIG. 1 is substantially a mirror image thereof.

I claim:

The ornamental design for a vacuum pick-up for wafers, as shown and described.
